(57) **CLAIM**

The ornamental design for the mounting back, as shown and described.

DESCRIPTION

FIG. 1 is a perspective view of the mounting back of the present invention, taken from right front with exemplary portion of grid and first hook in dashed lines.

FIG. 2 is a perspective view of the mounting back taken from right front with exemplary portion of grid and second hook in dashed lines;

FIG. 3 is a perspective view of the mounting back taken from right bottom with exemplary portion of grid and first hook in dashed lines;

FIG. 4 is a perspective view of the mounting back taken from right bottom with exemplary portion of grid and second hook in dashed lines;

FIG. 5 is an enlarged perspective of the mounting back taken from right front, shown in FIG. 1;

FIG. 6 is an enlarged perspective of the mounting back taken from right rear, shown in FIG. 3;

FIG. 7 is an enlarged front view of the mounting back, shown in FIG. 1;

FIG. 8 is an enlarged right side view of the mounting back, shown in FIG. 1;

FIG. 9 is an enlarged left side view of the mounting back; shown in FIG. 1;

FIG. 10 is an enlarged top view of the mounting back, shown in FIG. 1; and,

FIG. 11 is an enlarged bottom view of the mounting back, shown in FIG. 1.

The dashed lines shown in the drawings illustrate the environment and portions of the article and form no part of the claimed design.
